UNITED STATES PATENT OFFICE.

EDWARD THOMPSON WILLIAMS, OF NEW YORK, N. Y.

AIR-COOLED CONDENSER FOR REFRIGERATING-MACHINES.

1,313,363.

Specification of Letters Patent.

Patented Aug. 19, 1919.

Application filed July 8, 1918. Serial No. 107,725.

To all whom it may concern:

Be it known that I, EDWARD T. WILLIAMS, residing at New York, N. Y., have invented certain new and useful Improvements in 5 Air-Cooled Condensers for Refrigerating-Machines, of which the following is a full, clear, and exact description.

This invention relates to refrigerating machines operating on the usual principle, 10 in which a gas is alternately liquefied in a suitable condenser and expanded into an expansion chamber or coil. In liquefying a gas (ethyl chlorid, for example) the heat which kept it in gaseous form is liberated 15 and must be got rid of in some way, the common practice being to absorb it by means of water passed through cooling coils. In some situations this plan is not practicable because of insufficient water supply, 20 as for example in dry regions, on railway dining cars, etc. It is accordingly the object of the present invention to provide a refrigerating machine in which the condenser is air-cooled, the heat being absorbed 25 and carried off by a current of air created in any convenient manner. Another object is to provide a small and compact machine for household use, on railway dining cars, and in other places where a large machine 30 would be impracticable. To these and other ends the invention consists in the novel features and combinations hereinafter described.

I have selected for illustration and specific description herein a form of the invention intended particularly for railway use, but it is to be understood that the invention is not limited in that regard. I have also shown it embodied in a machine of the 40 general type described in my prior Patents Nos. 1,164,689 and 1,165,926, dated December 21, and 28, 1915, respectively, but it can be embodied in other types as well.

The accompanying drawing is diagrammatic in character and shows the machine in vertical section.

The compressor 10, preferably of the rotary type, is inclosed in a pump-chamber 11, and may be submerged in water or other 50 cooling liquid 12 to absorb heat liberated in the compressor, as in my prior patents mentioned above. The compressor is driven by an external motor 13, the driving connection being made across a well 14 which may

contain glycerin or other lubricant for the 55 working parts of the compressor, the lubricant being supplied to such parts through suitable passages not shown. In the upper part of the pump-chamber is a receptacle 15 for liquefied gas. The latter flows out 60 through a pipe 16 to the expansion valve 17, where it is expanded into the expansion coils 18. In expanding, the gas absorbs heat from the contents of the "refrigerator" 19 on which the machine is set and in which 65 the expansion chamber or coils are located. From the expansion coils the expanded gas goes back to the low pressure side of the pump 10, as compressed, and is discharged from the high pressure side through pipe 70 20 into the receptacle 15.

The receptacle or liquid-gas reservoir 15 is closed by a lid or closure 21, and above 75 is a housing or flue 22 containing cooling coils 23, the inlet end of which is open to the chamber or receptacle 15 above the liquefied gas therein while its end extends down into the liquid. If desired, the receptacle may be provided with a partition 21¹, depending from the closure 21 below 80 the surface of the liquefied gas and between the two ends of the cooling pipe 23. In such case the outlet end of the pipe need not extend into the body of liquefied gas in the receptacle. In this pipe 23 the compressed gas is cooled to the point of liquefaction 85 and is delivered by gravity to the reservoir 15.

For the purpose of creating a suitable current of air through the housing 22 to 90 take up and carry off the heat radiated from the coils 23 the housing may be provided with a vertical flue 24. If the draft thus produced is not sufficient for the purpose a fan may be employed. In such case I 95 prefer to make the air-inlet in tubular form, 25, and put the fan therein, as shown at 26. The fan may be driven in any convenient manner, as by means of a belt 27 from the motor 13. Above the flue 24 is a cowl or 100 hood 27 to carry the warmed air to the outer atmosphere, say through the car roof 28. The cowl is preferably rotatable, and provided with a vane 29 so as to keep its discharge opening out of the wind and, in the 105 case of a railway car, to keep the cowl turned toward the rear as respects the direction of the car's motion. This insures that

the flow of air upwardly through the housing 22 will be helped, rather than hindered, by the wind and the movement of the car.

As stated above, the invention is not limited to the construction herein described but can be embodied in other forms without departure from its spirit.

I claim:—

- 10 1. In a refrigerating machine, in combination, a pump-chamber having a receptacle for liquefied gas, a compressor arranged in the pump-chamber, a cooling chamber or housing mounted on the pump-chamber and above said receptacle, a condensing coil arranged in the housing, to receive compressed gas and deliver the same in liquid form to said receptacle, and means for creating a current of air through the housing and about said condensing coil to cool the gas therein.
- 15 2. In a refrigerating machine, in combination, a pump-chamber having a receptacle for liquefied gas, a compressor in the pump-chamber, a cooling chamber or housing mounted on the pump-chamber above the said receptacle and having a vertical flue extending from its upper portion and an air-admission opening in its lower portion, and a condensing coil arranged in said housing, receiving gas from the compressor and delivering the same to the receptacle for liquefied gas.
- 20 3. In a refrigerating machine, in combination, a pump-chamber having a receptacle for liquefied gas, a compressor in the pump-chamber, a condensing coil above the pump-chamber, receiving gas from the compressor and delivering the same to the liquefied-gas receptacle, a housing inclosing the condensing coil and having an outlet at its top, and

a blower arranged to blow air into the lower portion of the housing.

4. In a refrigerating machine, in combination, a pump-chamber having a receptacle for liquefied gas, a compressor in the pump-chamber, a condensing coil receiving gas from the compressor and delivering the same to the liquefied gas receptacle, a housing inclosing the condensing coil, having an air-admission opening in its lower portion, a vertical flue extending from the top of the housing, and a rotary elbow-cowl at the top of the flue, provided with a vane to keep the elbow of the cowl out of the wind.

5. In a refrigerating machine, in combination, a pump-chamber having in its upper part a transverse receptacle for liquefied gas, a compressor in the lower portion of the pump-chamber below the liquefied-gas receptacle, a condensing coil above the pump-chamber, receiving gas from the compressor and delivering the same to the liquefied gas receptacle and having an air-outlet at its top, a blower at the lower part of the housing to blow air into the same, and a motor connected with the compressor and the blower to drive both.

6. In a refrigerating machine, in combination, a pump chamber, a compressor in the pump chamber, a condensing coil above the pump chamber to receive compressed gas from the compressor, and a vertical cooling chamber or housing above the pump coil and inclosing the condensing chamber and having means for causing a flow of air through the housing to cool the condensing coil.

In testimony whereof I hereunto affix my signature.

EDWARD THOMPSON WILLIAMS.

It is hereby certified that in Letters Patent No. 1,313,363, granted August 19, 1919, upon the application of Edward Thompson Williams, of New York, N. Y., for an improvement in "Air-Cooled Condensers for Refrigerating-Machines," errors appear in the printed specification requiring correction as follows: Page 2, line 73, claim 6, for the word "coil" read *chamber*; same page and claim, line 74, for the word "chamber" read *coil*; and that the said Letters Patent should be read with these corrections therein that the same may conform to the record of the case in the Patent Office.

Signed and sealed this 16th day of September, A. D., 1919.

[SEAL.]

M. H. COULSTON,
Acting Commissioner of Patents.
